BIN PILING APPARATUS

Benjamin P. Astley, Holyoke, Mass., assignor to B. F. Perkins & Sons, Inc., Willimansett, Mass., a corporation

Application March 14, 1956, Serial No. 571,576

2 Claims. (Cl. 68—177)

This invention relates to improvements in bin piling apparatus of the type shown and described in U. S. Letters Patent 1,478,846 of December 25, 1923, to P. W. Bidwell.

The principal objects of the invention are directed to cloth rope guiding or laying mechanism for bin piling apparatus of the type referred to in said patent wherein an elongated protective sleeve is provided for an elongated right and left hand screw which moves a pot-eye for a cloth rope back and forth in piling the cloth in a bin or vat.

A bin piler is used in textile plants and over a vat or bin and the like wherein cloth is laid for processing. The screw of the bin piler is disposed for horizontal rotation in one direction and a pot-eye is moved back and forth by the screw. A follower of the pot-eye is in engagement with the right and left hand screw threads or grooves of the screw so that it traverses the screw back and forth, for laying the rope of cloth in a bin or vat.

A web of cloth for laying in the vat or bin is bunched up somewhat in the form of a rope and is passed through the pot-eye for laying of the cloth in the vat or bin.

No end of difficulty has been experienced with bin pilers due to lint and the like settling on the traverse screw and drippings therefrom onto cloth therebelow.

Lint and other substances on the screw not only interfere with the smooth operation of the apparatus but also bring about abrasion of the parts so that wear is excessive.

The screw and follower must be lubricated and such not only contributes to the collection of lint and abrasive substances, but also drippings of lubricant from the screw onto the cloth in the bin is injurious and objectionable.

According to one novel feature of the invention, a screw shell is provided around the screw which prevents lint and foreign substances from settling thereon thereby to insure smooth operation and less wear caused by abrasion, and the shell provides a means for adequate lubrication of the screw without the danger of drippings of lubricant onto cloth in the bin therebelow.

According to another novel feature of the invention, the pot-eye component is reciprocable along the screw shell by which it is supported. In this manner, the pot-eye component is supported independently of the screw so that the screw is not burdened by the weight of the pot-eye and the cloth of rope therein so that wear of the screw by the pot-eye component is eliminated.

The foregoing is accomplished by mounting the pot-eye component on the screw shell for its back and forth reciprocation.

Various novel features of the invention will be observed from the following description of the present preferred form thereof and it will be observed that changes and modifications may be made in the apparatus without departing from the spirit and scope of the invention set forth in the appended claims.

In the drawings:

Fig. 1 is a side elevational view of cloth guiding or laying mechanism of the invention;

2

Fig. 2 is a plan view of the carriage of the mechanism, shown in Fig. 1;

Fig. 3 is a plan view of an end portion of the shell of the mechanism, shown in Fig. 1;

Fig. 4 is a sectional elevational view through the end portion of the shell and of the carriage; and

Fig. 5 is a sectional elevational view on the line 5—5 of Fig. 4.

Referring now to the drawings in detail, the novel features of the invention will be fully described:

So much of a bin piler, as opposite side portions 2 and 4, are shown as is necessary in order to describe the invention in the present preferred form thereof. The portions 2 and 4 correspond to the side members 20 of the carriage 5 of Patent #1,478,846, previously referred to.

An elongated shell 6 for a traverse screw extends between said end portions and a traverse screw 8 extends within and longitudinally of the shell. Opposite ends of said screw are journaled for rotation in bearings 10 shown as secured to the end portions 2 and 4. The screw 8 may be rotated at either end by suitable driving mechanism associated with either side portion of the piler carriage.

The shell and screw will be mounted horizontally so that a longitudinal slot 12 of the shell will be disposed along the upper side thereof. Opposite ends of the shell may be secured to the bearings 10 by any suitable means.

The screw 8 is provided with helically and longitudinally extending right and left hand follower grooves 14 and 16 which intersect or cross one another.

A carriage 18 is provided with a bushing or bearing 20 on and around the sleeve 6 for easy reciprocation of the carriage back and forth along said sleeve. Said bushing will be of such material as to require no appreciable amount of lubricant, if any at all, along the sleeve. Various commercial bushing materials are available for the purpose.

A follower 22 is provided which has a lower inner arched or more or less semi-circular portion 24 which is engageable in the threads or grooves of the screw.

An upper outer end 26 of the follower in the form of a stem or pin 26 is oscillatable in a follower holder or block 28. Said block extends through and is slidable up and down in a suitable opening provided in the upper side of the carriage.

The block 28 is secured to the lower side of a plate 30 by rivets, screws or the like indicated by 32. Plate 30 is connected to the upper side of the carriage by screws 34.

The block 30 may be readily removed by removing the screws 24 for access to the follower. A spring 36 between the stem of the follower and plate 30 urges the follower into the grooves of the screw.

The upper side of the shell 6 is provided with a transverse slot 12' which intersects the slot 12, as shown in Fig. 3. By aligning the follower 22 with the slot 12' and removing plate 30 from the carriage, the follower may be removed.

The carriage 18 has a depending portion 40 which is slidable along a guide rod 40'. Said guide rod 40' has its opposite ends fixed in brackets 2' and 4' which are secured to the side members 2 and 4. The guide rod 40' prevents turning of the carriage 18 about the shell 6.

P represents a pot-eye, of usual form, which is carried by the carriage 18 and through which a rope of cloth passes that is to be laid in a bin as the carriage moves back and forth on the shell.

In operation, the screw is rotated in one direction. The grooves of the screw at the ends thereof are so arranged that as the follower reaches the end of the groove of one hand said follower is turned on its stem so as to

enter the entrance end of the groove of the other hand. Thus, as the screw rotates, the carriage is moved back and forth on the shell. The connected ends of opposite grooves are shown at 15 in Fig. 4.

It will be noted that the carriage is reciprocable on the shell so as to relieve the screw of weight. The screw is protected against foreign substances settling thereon while at the same time said screw may be adequately lubricated without danger of drippings therefrom.

It will be noted that the screw and shell are out of contact so as to provide a longitudinal space therebetween and that the carriage is not only reciprocable along the sleeve but also supported entirely thereby to relieve the screw of its weight. The spacing of the screw and shell not only provides for adequate lubrication of the screw and follower but also there may be deflection of the shell due to the weight of the carriage and cloth supported thereby without affecting the screw.

What it is desired to claim and secure by Letters Patent of the United States is:

1. Apparatus for guiding a cloth rope and adapted for association with the horizontally spaced side members of the carriage of a bin piler comprising in combination, an elongated tubular shell having opposite ends fixed to bearings adapted to be secured to horizontally spaced side members of a bin piler carriage, a traverse screw having right and left hand intersecting helical grooves ex-

tending along and within said shell journalled at opposite ends in said bearings for rotation relative to said shell, a carriage surrounding and slidably supported by said shell for movements back and forth along said shell, said shell provided with a longitudinally extending slot on the upper side thereof, said carriage provided with an opening in the upper side thereof, a plate and means removably securing said plate to the upper side of said carriage, a holder secured to and depending from said plate into and through the opening of said carriage and longitudinal slot of said shell, said holder provided with a vertical bore, a follower having an upper portion oscillatable in the bore of said holder and a lower portion operatively engaging the grooves of said screw, and said shell provided with a slot in the upper side thereof crossing the longitudinal slot thereof for removal of the follower therethrough on removal of said plate and holder from the carriage.

2. Apparatus for guiding a cloth rope set forth in claim 1 wherein the outer side of said screw is slightly out of contact with the inner side of said shell, to provide an annular space between said screw and shell.
